Primary Examiner — Selina Sikder

(74) Attorney, Agent, or Firm — Law Offices of Lisa & Lesko LLC; Justin Lesko, Esq.

(57) **CLAIM**

I claim the ornamental design for a flush mount electrical box assembly, substantially as shown and described.

DESCRIPTION

FIG. 1 is a front perspective view of the flush mount electrical box assembly.

FIG. 2 is top view of FIG. 1.

FIG. 3 is a bottom view of FIG. 1.

FIG. 4 is a left side view of FIG. 1.

FIG. 5 is a right side view of FIG. 1.

FIG. 6 is a front view of FIG. 1; and,

FIG. 7 is a back view of FIG. 1.

1 Claim, 3 Drawing Sheets(56)
